PUMP BY-PASSING ASSEMBLAGE

Vernon F. Dale and George W. Reed, Onalaska,
Wis., assignors to The Bump Pump Co., La
Crosse, Wis., a corporation of Wisconsin

Application January 25, 1950, Serial No. 140,466

2 Claims. (Cl. 103—42)

1

Our invention relates generally to improvements in the art of propelling liquids through conduits or the like, and relates more specifically to improvements in the construction and operation of positive displacement liquid propelling pumps especially adapted to handle commodities such as milk.

The primary object of the present invention is to provide an improved rotary positive displacement pump which is simple, compact and durable in construction, and which is also highly efficient in operation.

It has heretofore been rather common practice to provide various types of pumps with some form of relief mechanism for by-passing fluid from the discharge to the intake sides of the pistons when excessive pressures are established at pump outlet or discharge. When applying such pressure relief devices to rotary positive displacement pumps for liquid, it has been customary to provide a spring pressed by-pass valve operable by the pump discharge pressure and located in a liquid return conduit some distance from the impeller displacement chamber, in order to accomplish the desired result. While this type of relief mechanism functions to release the abnormal pressures in a fairly satisfactory manner, it is objectionable when used in pumps for transporting commodities such as milk which are apt to become rancid if pocketed in a confined space for any length of time, as is often the case when relatively long by-pass conduits leading to and from the relief valve are employed and this valve is not opened for a prolonged period. Besides being relatively complicated and difficult to clean, the previous pressure release and by-pass mechanisms are therefore not sufficiently sanitary and are especially unsuitable for propelling milk and similar delicate commodities which are subject to spoilage.

It is therefore an important object of our present invention to provide an improved pump and relief unit which definitely eliminates undesirable pocketing of liquid, and which is adapted to be maintained in most sanitary condition at all times.

Another important object of the invention is to provide an improved positive displacement rotary pump having an effective pressure relief device incorporated directly therein, and adapted to establish a by-pass passage of limited size, only when abnormal discharge pressures are attained.

A further important object of this invention is to provide a conveniently adjustable liquid by-pass mechanism for rotary impeller positive dis-

placement pumps, wherein pocketing of liquid is avoided at all times, and which functions quickly and automatically to release abnormal liquid pressures.

Still another object of our invention is to provide a combined pump and pressure relief means, all parts of which are rapidly and conveniently accessible for inspection and cleaning, and which may be manufactured and sold at moderate cost for diverse purposes.

An additional object of the present invention is to provide a sanitary rotary liquid pump of the double impeller type, which is composed of only a few simple and sturdy parts and which requires minimum attention in order to maintain the same in effective operating condition.

These and other more specific objects and advantages of the present invention, will be apparent from the following detailed description.

20 A clear conception of the improvements constituting our present invention, and of the construction and operation of a typical pump unit embodying the same, may be had by referring to the drawings accompanying and forming a part of 15 this specification in which like reference characters designate the same or similar parts in the various views.

Fig. 1 is an end view of a typical double impeller rotary positive displacement liquid pump and by-pass unit constructed in accordance with the invention;

30 Fig. 2 is a central transverse section taken through the unit of Fig. 1 along the line 2—2, and showing a by-pass adjusting wrench in dot-and-dash lines; and

35 Fig. 3 is a fragmentary section similar to that of Fig. 2, taken through the by-pass or pressure relief mechanism, but showing the pressure release member in action.

40 In accordance with our present improvement we provide one wall of the displacement chamber of a positive displacement rotary pump with a bounding section adapted to be moved by excessive pressure away from the adjacent impellers so as to produce a relief passage only when abnormal discharge pressures are attained; and while the invention has been shown and described as being especially adapted for application to double impeller milk transporting pumps, it is not our desire to unnecessarily restrict the utility by virtue of this limited disclosure, and it is moreover contemplated that descriptive terms used herein be given the broadest possible interpretation consistent with the disclosure.

45 50 55 Referring to the drawings, the typical double

impeller rotary liquid pump and by-pass unit shown therein comprises in general, a main casing composed of a mid-section 6 and two opposed end closures or sections 7, 8 all coacting with each other to produce a displacement chamber 9 having a liquid inlet conduit 10 and a discharge or outlet conduit 11 communicating with the opposite sides thereof; a pair of oppositely rotatable constantly sealingly contacting rotors or impellers 12, 13 snugly confined and revolvable within the chamber 9 and adapted to be driven by shafts 14 extending through the closure section 7; a rigid movable plug or cylindrical member 15 slidably confined within a central bore 16 formed in the closure section 8 mid-way between the conduits 10, 11, and overlapping the contact zone between the impellers 12, 13; and adjustable means for normally urging the member 15 into sealing engagement with the adjacent end faces of the impellers 12, 13.

The three sections 6, 7, 8 are adapted to be firmly but detachably clamped to each other with the aid of studs 18 and nuts 19, so that the plane inner end surfaces 20, 21 of the closure sections 7, 8 respectively will sealingly engage the adjacent end surfaces of the impellers 12, 13; and the peripheral surfaces of the impeller lobes are likewise sealingly cooperable with the bores 22 of the casing mid-section 6. The periphery of the rigid by-pass plug or member 15 is provided with a resilient sealing ring 23 which slidably engages the bore 16 of the face plate or closure section 8, and the shafts 14 which normally rotate the impellers 12, 13 in opposite directions as indicated by the arrows in Fig. 1, may be driven in any suitable manner. The outer extremities of the conduits 10, 11 may also be provided with screw threads 24 for facilitating attachment to liquid supply and discharge sources with the aid of quick-detachable couplings.

The adjustable means for constantly but resiliently urging the plug member 15 inwardly toward the impellers 12, 13, comprises a U-shaped bracket or yoke 25 which is secured at its opposite ends to the casing section 8 by means of screws 26 and the medial portion of which is provided with an internally screw threaded boss 27; a helical compression spring 28 one end of which coacts with a socket 29 formed in the member 15 while its opposite end embraces and reacts against a retainer 30; and an adjusting screw 31 coacting with the screw threads of the boss 27 and with a central recess in the retainer 30. The outer end of the adjusting screw 31 is provided with a polygonal socket to which an adjusting wrench 32 may be applied as indicated in Fig. 2, in order to vary the compression of the spring 28 and to thereby vary the pressure required to displace the valve member 15, and the bracket attaching screws 26 may also be provided with similar polygonal manipulating sockets. A lock nut 33 may also be applied to the screw 31 and caused to coact with the boss 27 as shown, in order to maintain the retainer in adjusted position.

When the improved pump has been properly constructed and assembled as hereinabove described, and the inlet and outlet conduits 10, 11 have been connected to a liquid transporting line with the aid of the screw threads 24, the impellers 12, 13 may be rotated by means of the driving shafts 14 so as to cause liquid to be sucked into the displacement chamber 9 through the conduit 10 and to be discharged through the conduit 11. The spring 28 should then be ad-

justed by manipulating the screw 31 with the aid of the wrench 32, so as to normally maintain the inner face of the valve member 15 in the plane of the inner surface 21 of the closure plate or section 8 as in Fig. 2, thus normally producing sealing engagement between the member 15 and the impellers 12, 13 at the zone of contact of these impellers with each other while permitting the member 15 to move outwardly from this zone in case excessive pressure is created in the discharge space. If the discharge pressure does not exceed that required to displace the by-pass member 15, this member will remain in the position shown in Fig. 2 and no pocket or appreciable clearance will exist between the impellers 12, 13 and the relief member 15; but when the delivery pressure rises for any reason to an extent sufficient to overcome that exerted by the spring 28, the member 15 will be lifted more or less as depicted in Fig. 3 so as to permit immediate release of the excess discharge pressure by allowing liquid to return directly to the inlet space of the pump.

It will thus be apparent that we have in fact provided a combined pump and relief valve assemblage wherein excessive discharge pressure above any established value, will be quickly and automatically relieved without introducing objectionable pockets or space wherein liquid can accumulate for prolonged periods of time. As soon as the abnormal pressure is disbursed, the spring 28 will immediately return the member 15 to sealing position and will wipe out the clearance or by-pass space, so that the pump may thereafter operate normally with the impellers 12, 13 totally sealed. The packing ring 23 positively prevents undesirable escape of liquid through the bore 16 and is preferably located as near as possible to the inner face of the member 15 in order to eliminate undesirable pocketing of liquid; and by forming the member cylindrical manufacture and assembly thereof are facilitated. The entire pump structure is durable and of utmost simplicity, and all parts thereof are obviously readily accessible for inspection and clearing thus making it possible to maintain the assemblage in most sanitary condition at all times. The improved relief mechanism has proven highly successful and satisfactory in actual use as applied to milk transporting or pumping units, but may be advantageously and readily applied to other types of pumps for diverse purposes.

It should be understood that it is not desired to limit this invention to the exact details of construction and operation of the typical pumping unit, herein shown and described, for various modifications within the scope of the appended claims may occur to persons skilled in the art.

We claim:

1. In a rotary pump, a casing having a mid-section and opposed end sections secured thereto, said mid-section being provided with adjoining parallel bores communicating at the opposite sides of their junction with liquid inlet and outlet conduits and both of said end sections having plane parallel surfaces enclosing the opposite ends of said mid-section bores, one of said end sections being provided with a bore disposed coaxially of said junction and having a diameter approximately equal to the distance between the axes of said mid-section bores while the other end section is provided with spaced bearings disposed coaxially of said adjoining mid-section bores, a positive displacement rotor mounted in

each of said adjoining mid-section bores and normally sealingly engaging said end section plane surfaces and each other between said inlet and outlet conduits, each of said rotors having a supporting shaft projecting from one side only and journalled in one of said bearings while its opposite side is plane and devoid of projections, a cylindrical piston member snugly slidably confined within said end section bore and having a plane inner end surface normally sealingly co-operable with said plane rotor end surfaces while its outer end surface is constantly exposed to the ambient atmosphere, and means for resiliently urging said member toward said rotors.

2. In a rotary pump, a casing having a mid-section and opposed end sections secured thereto, said mid-section being provided with adjoining parallel bores communicating at the opposite sides of their junction with liquid inlet and outlet conduits and both of said end sections having plane parallel surfaces enclosing the opposite ends of said mid-section bores, one of said end sections being provided with a through bore disposed coaxially of said junction and having a diameter approximately equal to the distance between the axes of said mid-section bores while the other end section is provided with spaced bearings disposed coaxially of said adjoining mid-section bores, a positive displacement rotor mounted in each of said adjoining mid-section bores and normally sealingly engaging said end

section plane surfaces and each other between said inlet and outlet conduits, each of said rotors having a supporting shaft projecting from one side only and journalled in one of said bearings while its opposite side is plane and devoid of projections, a cylindrical piston member snugly slidably confined within said end section bore and having a central outer recess and a plane inner end surface normally sealingly co-operable with said plane rotor end surfaces while its outer end surface is constantly exposed to the ambient atmosphere, a helical compression spring disposed externally of the casing for urging said member toward said rotor and having one end confined within said recess while its opposite end is provided with a reaction plug, and means coacting with said plug for varying the tension of said spring.
